(57) **CLAIM**

The ornamental design for a motor vehicle surveillance camera, as shown and described.

DESCRIPTION

FIG. 1 is a perspective view of a motor vehicle surveillance camera showing the new design;

FIG. 2 is a front view of the motor vehicle surveillance camera shown in FIG. 1;

FIG. 3 is a rear view of the motor vehicle surveillance camera shown in FIG. 1;

FIG. 4 is a left side view of the motor vehicle surveillance camera shown in FIG. 1;

FIG. 5 is a right side view of the motor vehicle surveillance camera shown in FIG. 1;

FIG. 6 is top plan view of the motor vehicle surveillance camera shown in FIG. 1; and,

FIG. 7 is a bottom view of the motor vehicle surveillance camera shown in FIG. 1.

The portions of the camera in broken lines are shown for illustrative purposes only and form no part of the claimed design.
